WALL BOX FOR WATER TUBE BOILERS

George P. Reintjes, Kansas City, Mo.

Application November 23, 1946, Serial No. 711,876

1 Claim. (Cl. 122—6)

1

This invention relates to water wall furnaces and more particularly to a supporting beam construction at the point where the boiler tubes are brought outside the furnace for connection to a header, drum, or for any other purpose.

In usual designs of the general nature involved, the boiler tubes have heretofore been brought out of the furnace wall through a more or less elaborate and bulky girder structure spaced just above or below the customary horizontal beam that supports the load of that part of the furnace overlying the tubes. One form of construction in which I have eliminated the complexities of prior constructions is shown in my prior patent in which I bring the tubes through the horizontal beam.

This construction is satisfactory in those cases where the tube diameters and spacing are such that the tubes may enter a header, drum or the like, in a single row, but where the tubes are of such diameter or are so spaced as to require more than one row at the point where they enter a header or are otherwise directed, it has been found that the supporting beam must sometimes be reinforced or requires a heavier web than supplied by standard or commercial shapes.

The present invention, therefore, has for its prime object to provide a beam which can be fabricated of commercially available shapes, and will be strong enough to carry the overlying load, and will at the same time permit the tubes to be brought out of the furnace in any number of horizontal rows.

With the general objects named in view and others as will hereinafter appear, the invention consists in certain novel and useful features of construction and organization of parts as herein-after described and claimed; and in order that it may be fully understood, reference is to be had to the accompanying drawing, in which:

Figure 1 is a fragmental view of the upper end of a water wall furnace, partially cut away to illustrate the construction of the invention.

Figure 2 is a side elevation of the supporting upright, the header and the supporting fabricated beam, the refractory supporting means being omitted for purposes of clarity.

In the said drawing, where like reference characters identify corresponding parts in all of the figures, 1 is an upright or column forming the foundation of the steel supporting furnace framework, such uprights being arranged in spaced relation around the furnace chamber. Secured to the uprights in any suitable manner, not shown, is a furnace wall 2.

In certain furnace designs, the wall 2 is lined with a series of water tubes 3 which, at their upper ends, are bent outwardly through the furnace wall where they may be connected to a header or the like 4, or may be otherwise disposed of. In the construction illustrated, the tubes 3

are so close together that they must be connected to a header in two rows, see Figure 2, at different vertical levels, it being understood in this connection that the tubes may be brought out in any number of rows depending upon the design and size of the parts.

In order to carry the load of the overlying portion of the furnace wall and permit the tubes to extend therethrough, a fabricated horizontal beam is carried by the uprights 1, said beam, as illustrated, comprising a pair of reversely facing bridge members, such as, channels 5 and 6, formed in a unitary structure by diagonal reinforce members, as shown by T-irons 7 and 8, to provide a reticulated beam formed with openings for the tubes, the reinforce members being welded or otherwise secured to any part of the channels or bridge members of other shape.

The beam carries a box stringer 9 from which tile hangers 10 are suspended, said hangers supporting refractories 11 and 12 of such length and shape as to closely conform to the curvature of the particular tube underlying the same. The space under the tubes 3 is closed by a series of tile 13 and 14 respectively conforming to the curvature of the lower side of the tubes, and supported on hangers 15 carried by stringer boxes 16 secured to the uprights 1.

From the above description it will be apparent that I have produced a construction possessing all of the features of advantage set forth as desirable, and while I have described and illustrated the preferred construction, it is to be understood that I reserve the right to all changes within the spirit and scope of the appended claim.

I claim:

In a water tube boiler, the combination with an upright support, a horizontal beam carried by said support and comprising a pair of vertically spaced members connected by two sets of oppositely inclined spaced diagonals to provide tube-receiving openings, a plurality of water tubes spaced from the upright and having their upper ends curved horizontally, the horizontal portion of alternate tubes passing through the openings at different levels, tile supports respectively carried by the upright and the beam, and tile carried by said tile supports in coacting pairs to embrace the upper and lower faces of the curved portion of each water tube.

GEORGE P. REINTJES.
